[57] CLAIM

The ornamental design for ophthalmic spectacles, substantially as shown and described.

DESCRIPTION

FIG. 1 is a front view of ophthalmic spectacles showing my new design;

FIG. 2 is a fragmentary rear view thereof;

FIG. 3 is a perspective front view thereof; and
FIG. 4 is a fragmentary cross-sectional view thereof taken along line 4—4 of FIG. 2.

The temples are fragmentarily shown in FIGS. 2 and 4 for convenience of illustration. The characteristic feature of the design resides in the curved arches at the top rear portion of the rims.
